UNITED STATES PATENT OFFICE

2,565,390

ELECTRIC MATTRESS HEATER

David Mitnowsky, Newark, N. J.

Application December 28, 1949, Serial No. 135,435

1 Claim. (Cl. 219—46)

1

My invention relates generally to mattress heaters and specifically to that type having electrically energized heat generating elements.

It is among the objects of my invention to provide a mattress heater that is safe.

It is another object of my invention to provide a mattress heater that generates heat and readily disseminates it throughout the mattress.

Yet another object of my invention is to provide a mattress heater that has a large radiation area.

Among the objects of my invention is to provide a mattress that is simple in form, durable, inexpensive, easy to construct and maintain.

These objects and advantages, as well as many other objects and advantages, may be attained by the device illustrated in the drawings, in which:

Figure 1 is a view in perspective of my mattress heater with the top plate raised;

Figure 2 is a view in perspective with the top plate closed; and

Figure 3 is a plan view showing the mattress heater in a mattress.

Referring now to the drawings in detail, my mattress heater has a top radiation plate 11 and a bottom radiation plate 12. These plates are attached together by hinges 13 affixed to their longitudinal edges. The plates 11, 12 are constructed of flexible metallic sheets, although other materials may be used. The plates are provided with many radiation holes 14 to permit the circulation of air between them.

Resistance wires 15 are enclosed between the plates. These wires have characteristics which will cause them to give off heat when electrically energized. Mounted on and completely covering each wire 15 are glass beads 16. They serve to insulate the wires and yet permit the radiation of the heat generated. Covering the beads are tubes 17 formed of good heat conducting material such as copper, aluminum, or the like. The tubes 17 are fastened to one of the plates 12, at appropriate intervals, by cleats 18. The ends of the wires are connected to a plug 19 which will receive another plug connected to the power source.

The tubes 17 are arranged as will appear from Figure 1. Between the tubes, a brace or rectangular slat 20 is attached to one of the plates 11, 12 by hinges 27. A slotted handle 25 is attached to the slat 20 by two screws 26 so that it may slide outwardly to the position indicated in Figure 2.

In use, a mattress 21 is constructed with its equatorial springs 22 split into equal halves as will appear in Figure 3. The mattress heater is placed between the halves of the springs 22. A zippered opening 23 in the mattress cover 24 gives access to the handle 25 and also permits the introduction of the power line.

2

When the slat 20 is down, as in Figure 1, it may be raised to the position shown in Figure 2, whereupon greater air circulation is permitted between the plates 11, 12. This also permits the removal of the sag that may occur in the center of the mattress, due to the flattening of the springs 22. A thermostat may be included within the mattress 21 to retain the degree of heat within the desired range.

10 I have referred to glass beads 16 as covering the wires. These beads need not necessarily be of glass but may be of some material which is a good conductor of heat. Preferably, they should be circular in form so as to keep the wires from contacting any parts of the plates 11, 12 and yet have the greatest radiating area to permit the heat to be freely circulated to all corners of the mattress.

Many other changes may be made in the construction, selection and arrangement of the various parts comprising my mattress heater, all within the scope of the appended claim, without departing from the spirit of the invention.

I claim:

25 A mattress heater comprising a resilient top plate, a resilient bottom plate pivotally attached to the top plate along its longitudinal edges, a brace pivotally attached to one of the plates, a handle slidably attached to the brace, a resistance wire disposed between the plates, beads covering the wire, a tube of heat conducting material covering the beads, means attaching the tube to one of the plates, and a plurality of holes in the plates.
